Primary Examiner — Steven J Czyz(74) *Attorney, Agent, or Firm* — Joe Nieh(57) **CLAIM**

The ornamental design for a child backpack carrier, as shown and described.

DESCRIPTION

FIG. 1 is a rear perspective view of a child backpack carrier showing our new design;

FIG. 2 is a rear view thereof;

FIG. 3 is a front perspective view thereof;

FIG. 4 is another front perspective view thereof;

FIG. 5 is another rear perspective view thereof;

FIG. 6 is a bottom view thereof;

FIG. 7 is a top view thereof;

FIG. 8 is a left side view thereof;

FIG. 9 is a front view thereof; and,

FIG. 10 is a right side view thereof.

The broken lines depict stitching that forms part of the claimed design.

1 Claim, 10 Drawing Sheets(56)
